UNITED STATES PATENT OFFICE.

ERNST AUGUST TOBORG, OF BIGGS, CALIFORNIA.

WINDMILL.

1,411,137.

Specification of Letters Patent. Patented Mar. 28, 1922.

Application filed April 25, 1921. Serial No. 464,239.

To all whom it may concern:

Be it known that I, ERNST AUGUST TOBORG, a citizen of the United States, residing at Biggs, in the county of Butte and State of California, have invented new and useful Improvements in Windmills, of which the following is a specification.

My present invention has reference to an improved construction in wind mills.

10 In carrying out my invention, it is my purpose to produce a wind mill with a wheel of a particular and peculiar construction whereby the vanes thereof will be in a position to receive the wind, regardless of the direction of the wind, and wherein the wheel is at all times automatically controlled when in motion and locked against motion when not required for pumping or other purposes.

It is also my purpose to produce a wind mill in which the wheel thereof is made up of spaced vertically disposed cross sectionally concavo-convex blades or vanes connected together by peripheral bands, the inner bands having radially directed spokes 25 leading to hubs on which the shaft for the wheel is secured, a revoluble element normally in the path of engagement with one of the outer bands of the wheel, and a governor actuated by the shaft for controlling 30 the frictional engagement of the revoluble member with respect to the band adjacent thereto, whereby the revolution of the wheel and the speed of the shaft is governed, while in addition to this, manually operable means 35 is also provided for forcing the revoluble element against the band and locking the wheel and shaft from turning, when the mill is not desired for use.

The foregoing, and many other objects 40 which will appear as the nature of the invention is better understood, may be accomplished by a construction, combination and operative association of parts, such as is disclosed by the drawings which accompany 45 and which form part of this specification.

In the drawings:

Figure 1 is an elevation of a wind mill constructed in accordance with this invention.

50 Figure 2 is a top plan view thereof.

Figure 3 is a sectional view on the line 3—3 of Figure 1.

Figure 4 is a sectional view on the line 4—4 of Figure 2.

55 Figure 5 is a sectional view on the line 5—5 of Figure 1.

Figure 6 is a sectional view on the line 6—6 of Figure 4.

The frame of my improved wind mill is preferably constructed of angle irons, including corner posts 1, cross members 2 connecting the corner posts, and brace means 3 between the lower series of cross pieces 2 and corner posts. The braces 3, at the top of the frame are reinforced by curved brace 60 members 4 and straight right angularly disposed brace members 5.

The cross pieces 2, next to the top cross pieces are reinforced by horizontal angularly arranged braces 6, and also there is 70 secured centrally between two of the opposed cross pieces 2 a flat plate 7. The plate 7 is centrally formed with an opening that provides a journal bearing for the vertically disposed shaft 8 of the wind wheel. The 75 shaft 8 also finds a bearing, at its upper end in an opening provided at the lapping portions of the cross braces 5. The shaft is provided with spaced hubs 9 and 10 respectively. Both the hubs have radiating spokes 80 14 respectively to which are secured ring members or bands 15 respectively. The bands 15 are preferably made up of segments, the ends of which being flanged against the spokes and bolted thereto, as at 85 17. Thus the ends of the spokes project a determined distance beyond the bands 15, and have their outer ends offset or flanged, as at 18 and connected by bolts or the like to outer bands 19 respectively. Disposed between the upper and lower spaced inner and outer pairs of bands are the vanes 20 for the wheel. Each of the vanes is preferably constructed from a single plate of metal or other light material which is rounded longitudinally upon itself so that each vane is concavo-convex in cross section. The edges of the vanes 20 at the top and bottom portions thereof are in frictional engagement with the respective inner and outer bands for the 90 spokes of the wheel, and passing through the said edges of the vanes and through the respective bands of the upper and lower spoke members are bolts or rods 21. The elements 21 materially reinforce the vanes at the portions thereof which are connected to the spaced flange, and in a like manner hold the said bands in proper spaced relation to each other.

On two opposed cross members 2, at the 110 lower portion of the frame there are supported plates which provide what I will

term a platform and which is indicated by the numeral 22. The platform is centrally reinforced by upright posts 23 that are secured to the base 24 on which the frame 5 rests. The platform is provided with a bearing 25 for the lower end of the shaft, and the said shaft, above its bearing has keyed thereon a beveled pinion 27. This pinion is in mesh with a similar pinion 28 which has 10 its shaft 29 journaled in bearings 30 on the platform and disposed laterally with respect to the platform. On the end of the shaft which projects beyond the platform there is a wheel 31. To this wheel there is eccentrically pivotally connected, as at 32, a pitman 33, which has its lower end loosely connected to the plunger rod for a pump 36. The turning of the wind wheel will, through the means just described, reciprocate the 15 pump rod. Arranged diagonally between one of the corner posts and the platform 22 is an auxiliary frame which includes a base 37 provided on its inner end with an upstanding lug 39 that has a web portion connecting the same to the post 38. The post 38, at its upper end is connected to one of the corner posts 1 of the main frame by a bar or plate 40, the same being secured to one of the horizontal braces between the 20 cross pieces 2 at the base or bottom of the wind wheel. The plate 40 and the base 37 of the auxiliary frame have elongated slots therethrough through which passes an arm 41. This arm is pivoted, as at 42 to the plate 25 40, and projects a suitable distance below the base plate 37, having its outer end received in a slotted guide 42' that is supported from the base 24 of the frame and one of the corner posts of the said frame. 30 The arm 41, at its upper end and on its inner face carries a roller 43 which is disposed opposite and in the path of contact with the outer lower band of the wind wheel. The roller has its shaft journaled in a suitable 35 bracket 44 on the inner edge of the lever. 40 The lug 39 is bifurcated and has pivoted therein the longer arm 45 of an angle lever. The shorter arm 46 of the angle lever has its end provided with an eye 47 through 45 which passes a bail-like member 48 that is secured on the inner edge of the arm 41. The arm 47 has its outer end provided with an elongated slot 49 that receives therethrough a pivoted pin 50 provided on the 50 angle end 51 of a lever 52. The lever 52 is pivoted, as at 53 in a slot adjacent to the upper end of the post 38, and has its outer end formed with a sleeve or collar 54 that surrounds the shaft 8 and which is contacted by a disk 55 that forms the head member of a governor. The disk has on its lower face opposed downwardly directed ears 56 to which are pivoted arms 57. The 55 arms 57 have their lower ends bifurcated 60 and are pivoted, as at 58 to arms 59 that

have their outer ends weighted, as at 60 and their inner ends pivoted, as at 61 to outstanding ears formed on a sleeve or collar 62 that is keyed or otherwise secured to the shaft 8. It will be apparent that the turning of the wind wheel and its shaft will swing the weighted arms of the governor, causing the arms or links that are connected to the disks to elevate the said disk and in so doing swing the angle lever on 70 its pivotal connection with the post and the angle lever which is pivotally supported on the lug, causing the latter to influence the arm 41 to bring the roller 43 into frictional engagement with the outer lower band of 75 the wind wheel, and thus regulate the turning of the wind wheel and shaft. By employing the pivoted roller 43, as a braking means, in lieu of an ordinary brakeshoe, a more gentle braking action is afforded. It 80 is not desirable that the wind wheel be brought to an abrupt stop as such might result in the breakage of parts, and the frictional engagement of the wheel 43 will, as above stated gradually bring the wind wheel 85 to a stop. On the guide there is means 63 for engaging with the arm and for locking the same in one position whereby the said arm is swung and the roller carried at the upper end thereof is forced into such frictional engagement with the outer lower band of the wheel so as to prevent the said wind wheel from turning. The construction of the vanes of the wheel is such that the wheel will be revoluble regardless of the 90 direction of the wind abutting thereagainst, and it is thought that the foregoing description, when taken in connection with the drawings will amply set forth the construction, operation and advantages of the 95 improvement. It is believed necessary to state, however, that the nature of the invention is such as to render the same susceptible to various changes and modifications which fall within the scope of what is claimed 100 and that I am therefore entitled to make such changes.

Having described the invention, I claim:

1. A wind wheel having a peripheral band, a shaft for the wheel, a pivotally supported arm, a roller carried thereby in the path of engagement with the band, and means between the shaft and arm, actuated by the rotation of the shaft for swinging the 115 arm to bring the roller into or out of frictional engagement with the band, in accordance with the speed of rotation of the shaft and wheel, and means, independent of said shaft operating means for locking the lever 120 in a position to cause the roller to engage the band with sufficient friction to prevent the turning of the wheel and shaft.
2. In a wind wheel, a frame, a vertically disposed shaft journaled therein, spaced 130

hubs on the shaft, anti-frictional means between the lower hub and frame, spokes radiating from the hubs, inner and outer bands secured to the spokes, said inner 5 bands being made up of segments that have their ends flanged, and bolted to the spokes, vertically disposed curved plates disposed between the inner and outer bands, elements 10 passing through the bands and plates holding the plates between the bands and spacing the bands, friction means in the path of contact with one of the outer bands, and means actuated by the turning of the wheel and shaft for regulating the engagement of 15 the friction means with the said band.

3. In a wind mill, a frame, a shaft journaled vertically and centrally therein, a wind wheel secured to the shaft and comprising cross sectionally rounded vertically 20 disposed vanes disposed between inner and outer bands, spokes radiating from the shaft and connecting the inner and outer bands, a pivotally supported arm, a roller journaled in bearings at the upper end thereof,

and in the path of contact with one of the 25 bands of the wind wheel, a governor including an element which is slidable on the shaft, a pivotally supported angle lever having a collar surrounding the shaft and in the path of contact with the slidable element of the governor, a second pivotally supported angle lever loosely connected to the first mentioned angle lever, a loose connection between the last mentioned lever and the arm whereby when the first mentioned lever is influenced by the governor the last mentioned lever will swing the arm to bring the roller carried thereby in frictional engagement with the band of the wind wheel, guide means for the lower end 40 of the arm, and means carried by said guide means for locking the arm thereto and holding the roller in sufficient frictional engagement with the band to prevent the turning of the wheel and shaft. 45

In testimony whereof I affix my signature.

ERNST AUGUST TOBORG.
